PERSONNEL PARACHUTE PACK

Charles E. Carroll, Dayton, Ohio

Application June 4, 1952, Serial No. 291,818

4 Claims. (Cl. 244—148)

(Granted under Title 35, U. S. Code (1952), sec. 266)

The invention described herein may be manufactured and used by or for the United States Government for governmental purposes without payment to me of any royalty thereon.

This invention relates to parachute packs of the emergency free type, and particularly to an improved method of stowing the canopy in the envelope and means for carrying out the method.

The pack enclosure is of the envelope design having a back panel with four flaps which fold over the parachute canopy, coming together and lapping over slightly to form the front closure of the pack housing, the flap ends which overlap being provided with aligned openings, the openings being reinforced by grommets.

An improved means for locking the pack flaps closed is included in the design. Two or more cord loops are attached to the panel in positions which are in alignment with the axes of the grommets. The cord loops may then extend from their point of attachment to the back panel upward through the folds of the canopy then through the grommets. The rip cord pins are thus arranged to pass through the loop ends and thereby serve as locking members to hold the pack closed.

The construction of the pack will be clearly understood from the accompanying drawings, wherein

Fig. 1 shows the improved pack fully open and with the canopy arranged in folds and lying on the back panel preparatory to closing;

Fig. 2 shows the improved pack in the fully closed state;

Fig. 3 is a longitudinal sectional view taken at 3—3 of Fig. 2 through the locking means which also serves to keep the main chute from shifting in the pack;

Fig. 4 is a transverse section taken at 4—4 of Fig. 2.

Like reference characters refer to like parts throughout the several views.

Referring more particularly to Fig. 1, the fully open pack is seen to consist of a back panel 10 with right and left side flaps 12 and 14 and with top and bottom end flaps 16 and 18 integrally formed on the panel.

Grommets 20, 22, 24, 26, 28 and 30 line the openings in the outer free ends of the flaps 16, 18, 14 and 12. Cord loops 31 and 33 are anchored to the back panel 10 at points 32 and 34, which points are directly over the grommets 20, 22, 24, 26, 28 and 30 when the flaps are folded as in Fig. 2.

A rod 35 is sewed into the back panel 10 along its longitudinal axis, the sewing extending between the points 32 and 34, the ends of the rods extending slightly beyond the sewing whereby the cord loops may be removed and renewed when worn.

With the flaps 12, 14, 16 and 18 properly folded as in Fig. 2, three grommets 20, 24 and 26 are directly over the cord loop 31 and three grommets 22, 28 and 30 are directly over the cord loop 33. The rip cord pins 36 and 38 are attached to the rip cord cable 40. The operation of the herein disclosed parachute pack may preferably be substantially as follows:

2

When the canopy is being packed in the envelope it is laid in folds as seen at 42, Fig. 1, the cord loops 31 and 33 being brought up between folds of the canopy and threaded up through the grommets, after which the rip cord pins 36 and 38 are threaded through the upper ends of the cord loops which locks the flaps closed. Conversely, one pull on the cable 40 withdraws both pins 36 and 38 from the cord loops and thereby unlocks the entire pack.

10 The herein disclosed pack has the following advantages:

Due to the arrangement of the parachute on the back panel, as in Fig. 1, in the form of loops 42, with the cord loops 31 and 33 extending upwardly between turns of the canopy loops, the weight of the parachute when on the chutist's back is divided into three parts, one-third of the weight being above and resting on the cord loop 31, one-third being between the cord loops 31 and 33 and resting on the cord loop 33, the remaining third resting on the end flap 18 when the parachute is packed. This arrangement prevents shifting of the canopy in the envelope and avoids tangling. This is an important feature of this invention. Additionally:

It is more flexible due to the minimum use of metal stiffeners made possible by the action of the cord loops.

25 It is softer and more comfortable due to the use of cord loop locking means which permit loose stowage of the parachute canopy with minimum shifting in the arrangement of the canopy material.

It is lighter in weight because of the absence of metal locking cones, metal stiffeners, pack opening elastics, protective covers and snap fasteners.

It is less expensive due to simplicity of construction and reduction of expensive metal parts.

Having described an embodiment of my invention, I claim:

35 1. A parachute pack comprising a rectangular back panel, side and end flaps extending from the sides and ends of said back panel, two grommets in the free end of each side flap each spaced along a line parallel to the center line of the pack and as far from the center line as the width of the pack, one grommet in the free end of each end flap each spaced along the center line of the pack half as far from the end of the back panel as the length of the back panel minus the distances between the 40 grommets in the side flaps, anchor means spaced along the center line of the pack and spaced apart on transverse lines extending through the grommets in the side flaps, a parachute canopy laid upon said back panel folded back and forth on itself between the side flaps, transversely to the said center line of the pack in transverse loops, cord loops fast at one end in said back panel and rip cord pins passing through the free ends of said cord loops each of said cord loops carrying a proportional amount of the weight of the chute.

55 2. A parachute pack comprising a substantially rectangular flexible fabric back panel, flexible side and end closures flaps extending outwardly from the sides and ends of the back panel and foldable across the back panel, to inclose a folded parachute carried on the back panel with their free ends in overlapping relation, elongated cord loops secured to the inside of the back panel at spaced points along a median line between the side edges of the back panel, grommets fixed in the side and end flaps adjacent the free edges thereof to receive the cord loops 60 therethrough normal to the back panel with the side and end panels inclosing a parachute folded back and forth between the side flaps, carried on the back panel with said cord loops extending through the parachute between the folds thereof to prevent the chute from shifting toward the end flaps, and a rip cord comprising pull pin members extending through the outer looped ends of the

looped cords, across the grommets, exteriorly of the pack.

3. A parachute pack for receiving and retaining a parachute therein folded back and forth on itself comprising a flexible substantially rectangular back panel, flexible fabric side and end closure flaps extending from the opposite sides and ends of the rectangular panel, foldable across the back panel to inclose a folded parachute carried on the back panel with the free ends of the flaps in overlapping relation, elongated cord loops secured at their inner ends to the inside of the back panel at spaced points in a median plane, normal to the back panel, intermediate its side edges thereof, extending outwardly normal to said back panel, said side and end closure flaps having eyelets formed in the free overlapping edges thereof, disposed to receive the free looped ends of the loop cords therethrough with the eyelets in the overlapping edges in alignment, pull pins disposed through the looped ends against the eyelets to retain the flap ends in said overlapping relation, an elongated cover flap carried by the outermost flap extending over said eyelets and said looped ends, and a pull cable carried by another of said flaps and connected to said pull pins for withdrawing the pins from said loop ends to free the said flaps.

4. A flexible fabric personnel parachute pack comprising a flexible back panel substantially rectangular in shape having substantially triangular end and side flaps connected to the opposite ends and sides of the back panel and foldable toward each other over the back panel to dispose the edges thereof in overlapping relation, a rod retaining member disposed on the inside of the back panel and extending toward the end flaps beyond the

overlapping edges of said flaps in a median plane between the side edges of the back panel, a retainer patch secured over said rod to said back panel, endless elongated loop members having their inner ends looped over said rod in spaced relation to each other and extending through said patch substantially normal to the back panel to extend between the folds of a back and forth folded parachute carried on said back panel with the end and side flaps inclosing the parachute with said flap edges in said overlapping relation, grommets formed in said side flaps to receive the outer end loops of the loop member therethrough, a grommet formed in each of the end flaps disposed to align with one of the grommets in each of the side flaps to receive one of the outer end loops of the loop members therethrough, a pull pin extending through each of the outer loop ends of the loop members exteriorly of the flaps and across the edges of the grommets toward one of the end flaps, a pull cable carried by the last mentioned flap and connected to both of said pull pins for withdrawal thereof to free said flaps, and an elongated inclosure flap carried by one of the side flaps inclosing said pull pins and cable.
